UNITED STATES PATENT OFFICE.

WILLIAM EDWARD WILSON, OF LARIMER, PENNSYLVANIA.

ADJUSTABLE BLIND AND CURTAIN FIXTURE.

SPECIFICATION forming part of Letters Patent No. 745,129, dated November 24, 1903.

Application filed April 16, 1903. Serial No. 152,826. (No model.)

To all whom it may concern:

Be it known that I, WILLIAM EDWARD WILSON, a citizen of the United States, residing at Larimer, in the county of Westmoreland and State of Pennsylvania, have invented a new and useful Improvement in Adjustable Blind and Curtain Fixtures, of which improvement the following is a specification.

My invention relates to certain new and novel improvements in an adjustable window-blind fixture constructed so as to be made of different lengths and may be adjusted to the blind-rolls of various lengths. This is done by arranging the two sections of the fixture so that they slide along their sides, as will be more particularly described hereinafter.

In the accompanying drawings, forming a part of this specification, Figure 1 is a perspective view of my invention, showing the means of sliding the two sections back and forth. Fig. 2 is a top view of the same, with the blind and curtain-pole shown in position by dotted lines. Fig. 3 is a modified sectional view of one end of my invention, showing a hinged section.

In the drawings, the numeral 1 designates the body of one section of the window-blind fixture, and 2 is the other section.

3 is a slotted extension to the section 1, and 4 is the slotted extension to the other section 2.

5 is the slot in the part 3, and 6 is the slot in the part 4.

7 is the blind-roll bracket, having the opening 8 for the revolving spindle of the blind to rest in. 9 is the other bracket, having the cut-out 10 in which to seat the flat pintle of the blind-roller. These two brackets can be made integral with the sections 1 and 2, or they may be riveted on.

11 and 12 are hooks formed on the ends of the sections 1 and 2. These hooks afford a means of locking the two sections together and at the same time allow them to slide back

and forth, and thus reduce or lengthen the size of the fixture, so as to conform to the different lengths of blind and curtain-pole. 45

13 and 14 are openings for nails or screws by which to securely fasten the fixture to the top of the window-frame when the desired length has been attained, as aforesaid. 50

15 and 18 are brackets for supporting the curtain-pole. These brackets are seated in the slots 5 and 6 and held in position by the collar 16 and nut 17.

19 is a hinge formed in the sections 3 and 4, the object of which is to afford a means of adjusting the fixture in bay-windows or the like where it is desired to place the curtain-pole at some distance from the blind-fixture. When such is used, the brackets 15 and 18 will 60 be made angular in form, as seen in Fig. 3.

The hooks 11 and 12 are of such a form that they can easily be forced off from contact with the parts 1 and 2 and as easily replaced.

20 is the blind-roller, and 21 the curtain-pole. 65

Having thus fully described and shown my invention, what I claim as new, and desire to secure by Letters Patent, is—

A blind and curtain fixture consisting of 70 two similar slotted metal members, each formed at its inner end with oppositely-arranged hooks engaging the body of the other member to enable the members to be laterally adjusted, an angle-bracket struck up 75 from each member to form a shade-roller support, and pole-supporting brackets fitting and adjustable in the slotted outer ends of said members.

In testimony whereof I have hereunto signed 80 my name in the presence of two subscribing witnesses.

WILLIAM EDWARD WILSON.

In presence of—

W.M. M. LAUFFER,
J. F. ATKINSON.
